UNITED STATES PATENT OFFICE.

WILLIAM J. OWENS, OF UTICA, NEW YORK, ASSIGNOR TO SAYRE, OWENS & CO., OF SAME PLACE.

CHECK-DRAFT.

SPECIFICATION forming part of Letters Patent No. 395,917, dated January 8, 1889.

Application filed July 5, 1888. Serial No. 279,126. (No model.)

To all whom it may concern:

Be it known that I, WILLIAM J. OWENS, of the city of Utica, in the county of Oneida and State of New York, have invented certain new and useful Improvements in Check-Drafts; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in check-drafts.

The object of my invention is to provide a check-draft that is simple and effective, and that may also be operated by a chain or suitable connection from a distance.

In the drawings, Figure 1 shows a front view of my improved check-draft. Fig. 2 shows a top view of the device as shown in Fig. 1.

Like or similar letters and figures of reference refer to like parts in both figures.

Flue 1 is provided with an opening in the side closed by a head, 2, the head being a plain surface. A damper, 3, is provided in pipe 1, pivoted at 4 in the head 2 and the wall of flue 1, respectively. In the head 2 is an opening, 5, opening into the flue at one side of the damper, the opening being adapted to be closed by swinging cover 6, pivoted to the head 2. The swinging cover 6 is provided with a gear-sector, 7, which gear-sector partially surrounds the pivotal point of the swinging cover and is engaged by gear-sector 8. Gear-sector 8 is secured to the bearing 4 in the head 2 of the damper 3 and moves with it. A lever-arm, 9, is secured to gear-sector 8 and is provided for operating the same. A stop, 10, is provided for limiting the movement of the cover when the opening 5 is entirely closed thereby. A weight, 11, is provided upon arm 9 for automatically throwing the check-draft out of use and holding it in that position. A chain, 12, may be provided for operating the draft from a distance. The damper 3 is arranged with reference to swinging cover 6, so that when the cover is moved

from over the opening 5 the damper will stand crosswise of the flue, as shown in dotted lines in Fig. 1, and nearly close the same.

The operation of my device is substantially as follows: The current through the flue 1 being from the bottom toward the top as the device is shown in Fig. 1, and it being desired to apply the check-draft, the lever-arm 9 is raised into the position shown in full lines in Fig. 1, which movement moves, through the medium of the gear-sectors 8 and 9, the cover 6 from over the opening 5, and at the same time turns the damper 3 crosswise of the pipe, as it is shown in dotted lines in Fig. 1. By allowing the lever 9 to descend into the position shown in dotted lines in Fig. 1 the opening 5 is closed by cover 6 and the damper is turned lengthwise of the flue, so that the current through the flue is uninterrupted. When the opening 5 is entirely closed by swinging cover 6, the edge of the cover 6 comes in contact with stop 10, which limits the farther movement of the cover and also arrests the farther downward movement of arm 9.

The device can be used in any intermediate position between those described, if found desirable.

Various modifications which will readily suggest themselves may be made in my device without departing from the spirit of my invention.

What I claim as new, and desire to secure by Letters Patent, is—

1. The flue and opening therein, in combination with a pivoted lid having a gear-sector partially surrounding the pivotal point, the damper in the flue having an extended pivotal bearing, a weighted arm held to the end of the pivotal bearing of the damper, and a gear-sector on the pivotal bearing arranged to mesh with the gear-sector on the cover, substantially as set forth.

2. The head having an opening, in combination with a pivoted swinging cover having a gear-sector partially encircling the pivotal point of the cover, and the pivoted weighted arm having a gear-sector partially surrounding the pivotal point meshing into the gear-sector on the cover, arranged substantially as set forth.

3. The combination of the flue, the damper in the flue, the weighted arm for operating the damper, the swinging cover for closing and opening into the flue, and the gear-sectors 5 engaging each other, whereby the cover and damper are simultaneously movable, substantially as set forth.

In witness whereof I have affixed my signature in presence of two witnesses,

WILLIAM J. OWENS.
